(57) **CLAIM**

The ornamental design for a horticultural light fixture, as shown and described.

DESCRIPTION

Fig. 1.1 is a perspective view of the horticultural light fixture according to the design, showing the center portion in a vertical orientation, wherein the perspective is taken from a top thereof;

Fig. 1.2 is a bottom view of the horticultural light fixture illustrated in Fig. 1.1;

Fig. 1.3 is a top view of the horticultural light fixture illustrated in Fig. 1.1;

Fig. 1.4 is a left side view of the horticultural light fixture illustrated in Fig. 1.1;

Fig. 1.5 is a right side view of the horticultural light fixture illustrated in Fig. 1.1;

Fig. 1.6 is a front view of the horticultural light fixture illustrated in Fig. 1.1;

Fig. 1.7 is a rear view of the horticultural light fixture illustrated in Fig. 1.1;

Fig. 1.8 is a rear view of the horticultural light fixture illustrated in Fig. 1.1, showing the left side portion in a partially tilted position;

Fig. 1.9 is a rear view of the horticultural light fixture illustrated in Fig. 1.1, showing both left side portion and the right side portion in fully tilted positions;

Fig. 1.10 is a perspective view of the horticultural light fixture illustrated in Fig. 1.1, showing the center portion in a horizontal orientation;

Fig. 1.11 is a bottom view of the horticultural light fixture illustrated in Fig. 1.1, with the center portion in the horizontal orientation shown in Fig. 1.10;

Fig. 1.12 is a top view of the horticultural light fixture illustrated in Fig. 1.1, with the center portion in the horizontal orientation shown in Fig. 1.10;

Fig. 1.13 is a left side view of the horticultural light fixture illustrated in Fig. 1.1, with the center portion in the horizontal orientation shown in Fig. 1.10;

Fig. 1.14 is a right side view of the horticultural light fixture illustrated in Fig. 1.1, with the center portion in the horizontal orientation shown in Fig. 1.10;

Fig. 1.15 is a front view of the horticultural light fixture illustrated in Fig. 1.1, with the center portion in the horizontal orientation shown in Fig. 1.10;

(Continued)

Fig. 1.16 is a rear view of the horticultural light fixture illustrated in Fig. 1.1, with the center portion in the horizontal orientation shown in Fig. 1.10;

Fig. 1.17 is a rear view of the horticultural light fixture illustrated in Fig. 1.1, with the center portion in the horizontal orientation shown in Fig. 1.10 and with the left side portion in a partially tilted position; and

Fig. 1.18 is a perspective view of the horticultural light fixture in Fig. 1.1, showing the center portion in a vertical orientation, wherein the perspective is taken from a bottom thereof.

In the figures, broken lines denote aspects of the horticultural light fixture that form no part of the claimed design.
